United States Patent

Des. 242,406
Patented Nov. 23, 1976

242,406

FIRST-AID CABINET

David L. Romanoff, 29 E. 28th St.,
New York, N.Y. 10016

Filed Sept. 22, 1975, Ser. No. 615,582

Term of patent 14 years

Int. Cl. D6—04; D23—02

U.S. Cl. D6—104

FIG. 3

FIG. 1 is a top front perspective view of a first-aid cabinet showing my new design.

FIG. 2 is a rear bottom perspective view thereof.

FIG. 3 is a front perspective view of the cabinet in the open position.

I claim:

The ornamental design for a first-aid cabinet, as shown.
